AMINOALKOXY-DIPHENYL AMINES, ETHERS AND THIOETHERS

Jackson Pollard English, Princeton, and Frederick Louis Bach, Jr., Montvale, N.J., and Samuel Gordon, Pearl River, N.Y., assignors to American Cyanamid Company, Stamford, Conn., a corporation of Maine
No Drawing. Original application July 13, 1964, Ser. No. 382,383. Divided and this application Nov. 29, 1966, Ser. No. 597,523.

,523
10 Claims. (Cl. 260—268)

This application is a division of our copending application Ser. No. 382,383, filed July 13, 1964, which in turn is a continuation-in-part of our application Ser. No. 310,466, filed Sept. 20, 1963, now abandoned, which in turn is a continuation-in-part of our application Ser. No. 218,135, filed Aug. 20, 1962, now abandoned.

216,153, filed Aug. 20, 1902, now abandoned.

This invention relates to certain novel disubstituted-aminoethoxyphenyl amines, ethers and sulfides and, more particularly, is concerned with novel compounds which 20 may be represented by the following general formula:

wherein R₁, R₂, R₃ and R₄ are each hydrogen, methyl or ethyl with the proviso that the total number of carbon atoms in the alkylene group is less than 7; R₅ is lower alkyl; R₆ is lower alkyl; R₅ and R₆ taken together with the N(itrogen) is pyrrolidino, piperidino or 4-lower alkyl-1-piperazino; R₇ is hydrogen, nitro or amino; and Z is imino, oxygen or sulfur. Lower alkyl groups contemplated by the present invention are those having from 1 to 4 carbon atoms. The invention includes the novel disubstituted-aminoethoxyphenyl amines, ethers and sulfides and the method of lowering therewith the cholesterol level in blood serum.

Atherosclerosis is a form of arteriosclerosis where cholesterol and lipoid materials are deposited as plaques in the intima of large and medium sized arteries. Arteriosclerosis is associated with the degeneration of arterial walls by mechanisms not clearly defined. However, there is a statistical correlation between hypercholesterolemia and incidence of cardiovascular disease. For some time it has been considered desirable to lower high cholesterol and lipid levels as a possible preventive measure against atherosclerosis. In the past, attempts have been made to lower the level of cholesterol in the blood by the oral feeding of various substances which have been generally referred to in the art as hypocholesteremic adjuvants. Typical of such substances are lecithin, cottonseed oil and corn oil.

Our invention is based upon the discovery that our novel disubstituted-aminoethoxyphenyl amines, ethers and sulfides exert a more powerful hypocholesteremic action than the adjuvants which have been used heretofore. It is not known how the novel compounds of the present invention operate to lower the cholesterol level in blood serum and no theory of why these compounds so operate is advanced. It is not intended that the present invention should be limited to any theory as to mechanism.

The method of administering the novel compounds of the present invention is limited to oral administration. They may be orally administered, for example, with an inert diluent, or with an assimilable edible carrier, or they may be enclosed in hard or soft gelatin capsules, or they may be compressed into tablets. It is an advantage of the present invention that our novel compounds may be orally administered in any convenient manner.

The amount of a single dose or of a daily dose to be given will vary with the size of the individual to be treated, but should be such as to give a proportionate dosage of from 3 milligrams to 30 milligrams per kilogram of body weight per day. In terms of total weight, this is usually from about 0.2 gram to about 2.0 grams per daily dosage unit.

10 The novel compounds of the present invention may be readily prepared by the interaction of a p-disubstituted-aminoethoxy aniline, phenol or mercaptobenzene with an appropriately substituted p-nitrohalobenzene as set forth in the following reaction scheme:

wherein R_1 , R_2 , R_3 , R_4 , R_5 , R_6 , R_7 and Z are as previously defined; X is halogen and R_8 is hydrogen or an activating group such as carboxy ($-CO_2H$) or sulfoxyl ($-SO_3H$) which may later be removed. The reaction is preferably carried out in a solvent such as a lower alkanol, dioxane, tetrahydrofuran, and the like, at temperatures ranging from about $20^\circ C.$ to about $100^\circ C.$ over a period of time ranging from about 1 hour to 15 hours or more. The removal of the activating carboxy and sulfoxyl groups may later be accomplished by procedures well known in the art. When R_7 is nitro, this may later be reduced to an amino group with, for example, ammonium polysulfide.

The novel disubstituted-aminoethoxyphenyl ethers of the present invention may also be readily prepared by the interaction of p-hydroquinone with an appropriately substituted p-nitrohalobenzene as set forth in the following reaction scheme:

50 wherein R₇ and X are as previously defined. The intermediate p-hydroxy-nitrodiphenyl ether so obtained is then treated with an appropriate disubstituted-aminoethyl halide whereupon the desired disubstituted-aminoethoxy-phenyl ether is obtained. Advantageously, the intermediate 55 p-hydroxy-nitrodiphenyl ether is first converted to its alkaline metal alkoxide in an inert solvent such as toluene before treatment with the disubstituted-aminoethyl halide.

The novel disubstituted-aminoethoxyphenyl sulfides of the present invention may also be readily prepared by the interaction of phenol with an appropriate substituted p-nitrosulphenyl halide as set forth in the following reaction scheme:

70 wherein R_7 and X are as previously defined. The intermediate 4-hydroxy-4'-nitrodiphenyl sulfide so obtained is

then treated with an appropriate disubstituted-aminoethyl halide whereby the desired disubstituted-aminoethoxyphenyl sulfide is obtained. Again, it is preferred to convert the intermediate 4-hydroxy-4'-nitrodiphenyl sulfide to its alkali metal alkoxide in an inert solvent such as toluene prior to reaction with the disubstituted-aminoethyl halide.

The organic bases of this invention form non-toxic, acid-addition and quaternary ammonium salts with a variety of organic and inorganic salt-forming reagents. Thus, acid-addition salts, formed by admixture of the organic free base with an acid, suitably in a neutral solvent, are formed with such acids as sulfuric, phosphoric, hydrochloric, hydrobromic, sulfamic, citric, lactic, malic, succinic, tartaric, acetic, benzoic, gluconic, ascorbic, and related acids. Quaternary ammonium salts may be formed by reaction of the free bases with a variety of organic esters of sulfuric, hydrohalic, and aromatic sulfonic acids. The organic reagents employed for quaternary ammonium salt formation are preferably lower alkyl halides. However, other organic reagents are suitable for salt formation, and may be selected from among a diverse class of compounds including benzyl chloride, phenethyl chloride, naphthylmethyl chloride, dimethyl sulfate, methyl benzenesulfonate, ethyl toluenesulfonate, allyl chloride, methallyl bromide and crotyl bromide. For purposes of this invention the free bases are equivalent to their non-toxic acid-addition and quaternary ammonium salts.

The novel compounds of the present invention are, in general, colored materials which may be purified by distillation under reduced pressure. They are generally insoluble in water, but relatively soluble in organic solvents such as lower alkanols, esters, ethers, ketones, benzene, toluene, chloroform, and the like. The acid-addition and quaternary ammonium salts of the organic bases of the present invention are, in general, crystalline solids, relatively soluble in water, methanol and ethanol, but relatively insoluble in non-polar organic solvents such as ether, benzene, toluene and the like.

The invention will be described in greater detail in conjunction with the following specific examples.

EXAMPLE 1

4'-(2-diethylaminoethoxy)-4-nitrodiphenylamine

A solution of 4.2 g. of p-(2-diethylaminoethoxy)-aniline and 3.6 g. of potassium 2-chloro-5-nitrobenzoate in 50 ml. of water and 50 ml. of ethanol was refluxed for 15 hours and then extracted with two 100-ml. portions of chloroform. The aqueous raffinate was acidified with dilute hydrochloric acid whereupon a precipitate formed which was removed by filtration and dried. There was thus obtained 2.1 g. of crude 4'-(2-diethylaminoethoxy)-2-carboxy-4-nitrodiphenylamine which was placed in a distillation flask packed with glass beads and heated under reduced pressure. The solid mass melted and began effervescing at 180° C. (0.1 mm.). When decarboxylation was complete, the reaction mixture was cooled and triturated with sodium hydroxide solution. This crude solid was recrystallized from ethanol whereby there was obtained 4'-(2-diethylaminoethoxy)-4-nitrodiphenylamine, M.P. 86-88° C.

EXAMPLE 2

4'-(2-diethylaminoethoxy)-2,4-dinitrodiphenylamine

A solution of 4.2 g. of p-(2-diethylaminoethoxy)-aniline and 2.8 g. of 2,4-dinitrofluorobenzene in 100 ml. of ethanol was refluxed for 3 hours. The reaction mixture was then poured onto crushed ice, the insoluble red solid which separated was collected by filtration, and this crude material was recrystallized from ethanol whereby there was obtained 4'-(2-diethylaminoethoxy)-2,4-dinitrodiphenylamine, M.P. 70-71° C.

EXAMPLE 3

4'-(2-diethylaminoethoxy)-2-amino-4-nitrodiphenylamine

Alcoholic ammonium sulfide was added to a refluxing

ethanolic solution of 4'-(2-diethylaminoethoxy)-2,4-dinitrodiphenylamine. The cooled reaction mixture was treated with charcoal and filtered, and the filtrate was dried over anhydrous sodium carbonate. Passing dry hydrogen chloride gas through the dried filtrate precipitated the desired 4'-(2-diethylaminoethoxy)-2-amino-4-nitrodiphenylamine dihydrochloride, M.P. 179-181° C.

EXAMPLE 4

4'-(2-diethylaminoethoxy)-4-nitrodiphenyl ether

A mixture of 3.3 g. of p-hydroquinone, 1.2 g. of sodium hydroxide and 4.2 g. of 4-nitrofluorobenzene was refluxed for 15 hours and then cooled to room temperature. On standing, the desired intermediate, 4'-hydroxy-4-nitrodiphenyl ether, precipitated as a yellow granular solid. This intermediate was treated with 0.7 g. of sodium hydride in toluene followed by 4.1 g. of diethylaminoethyl chloride in toluene. Concentration of the reaction mixture gave a yellow oil which was purified by vacuum distillation. There was thus obtained the 4'-(2-diethylaminoethoxy)-4-nitrodiphenyl ether, B.P. 170-175° C./0.2 mm.

EXAMPLE 5

4'-(2-diethylaminoethoxy)-4-nitrodiphenyl sulfide

A solution of 11.2 g. of 4-nitrophenylsulphenyl chloride and 5.6 g. of phenol in 100 ml. of dry ether was allowed to stand overnight at room temperature. Concentration of the solution gave the desired intermediate, 4'-hydroxy-4-nitrodiphenyl sulfide, as a yellow solid. A toluene solution of this intermediate was treated with sodium hydride and then refluxed for 3 hours. The red brown suspension thus obtained was refluxed an additional 3 hours with diethylaminoethyl chloride whereby the desired 4'-(2-diethylaminoethoxy)-4-nitrodiphenyl sulfide was obtained as a yellow oil.

What is claimed is:

1. A member of the class consisting of compounds of the formula:

wherein R_1 , R_2 , R_3 and R_4 are each selected from the group consisting of hydrogen, methyl and ethyl with the proviso that the sum of the carbon atoms of

$$\text{R}_1 + \text{R}_2 + \text{R}_3 + \text{R}_4$$

is less than 5; R_5 is lower alkyl; R_6 is lower alkyl; R_5 and R_6 taken together with the N(nitrogen) is selected from the group consisting of pyrrolidino, piperidino and 4-lower alkyl-1-piperazino; R_7 is selected from the group consisting of hydrogen, nitro and amino; and Z is selected from the group consisting of $-\text{NH}-$, oxygen and sulfur; and the non-toxic acid-addition and quaternary ammonium salts thereof.

2. A compound according to claim 1 wherein R_1 , R_2 , R_3 and R_4 are each hydrogen; R_5 and R_6 are each ethyl; R_7 is hydrogen; and Z is $-\text{NH}-$.

3. A compound according to claim 1 wherein R_1 , R_2 , R_3 and R_4 are each hydrogen; R_5 and R_6 are each ethyl; R_7 is nitro; and Z is $-\text{NH}-$.

4. A compound according to claim 1 wherein R_1 , R_2 , R_3 and R_4 are each hydrogen; R_5 and R_6 taken together with the N(nitrogen) is 4-methyl-1-piperazino; R_7 is nitro; and Z is $-\text{NH}-$.

5. A compound according to claim 1 wherein R_1 , R_2 , R_3 and R_4 are each hydrogen; R_5 and R_6 are each ethyl; R_7 is amino; and Z is $-\text{NH}-$.

6. A compound according to claim 1 wherein R_1 , R_2 , R_3 and R_4 are each hydrogen; R_5 and R_6 are each ethyl; R_7 is hydrogen; and Z is oxygen.

7. A compound according to claim 1 wherein R_1 , R_2 , R_3 and R_4 are each hydrogen; R_5 and R_6 are each ethyl; R_7 is hydrogen; and Z is sulfur.

8. A compound according to claim 1 wherein R₁ and R₃ are each hydrogen; R₂, R₄, R₅ and R₆ are each methyl; R₇ is hydrogen; and Z is —NH—.

9. A compound according to claim 1 wherein R₁, R₂, R₃ and R₄ are each hydrogen; R₅ and R₆ taken together with the N(itrogen) is pyrrolidino; R₇ is nitro; and Z is oxygen.

10. A compound according to claim 1 wherein R₁ is

methyl; R₂, R₃ and R₄ are each hydrogen; R₅ and R₆ taken together with the N(itrogen) is piperidino; R₇ is amino; and Z is sulfur.
